United States Patent Office.

SAMUEL WELCH, OF BELPASSI, OREGON.

Letters Patent No. 99,379, dated February 1, 1870.

IMPROVEMENT IN GANG-PLOWS.

The Schedule referred to in these Letters Patent and making part of the same

To all whom it may concern:

Be it known that I, SAMUEL WELCH, of the town of Belpassi, in the county of Marion, State of Oregon, have invented a new and improved Mode of Attaching Plows to Carriages, regulating their depth, and of Applying Lever-Power to Gang and Sulky Plows.

I do hereby declare that the following is a full description thereof.

The nature of my invention consists in attaching plows to carriages by a sliding groove, and regulating the depth of the plow by a bolt with a joint in it, and two levers, constructed so as to raise the foremost end of the plow-frame first, then the other end, to a corresponding height, by applying power to one lever.

To enable others to use my invention, I will proceed to describe its operation.

Axle, A, to which the hounds N are attached by plates on both sides, terminating in bolts, which pass through a plate on the back of the axle, so that the hounds can be moved to the right or left at pleasure.

Post G is attached to axle A by a staple, with nuts on each end. It is fitted for groove F to work on, to raise and lower plow-frame. It also has a friction-roller for the end of lever B to rest on.

Groove F works on post G, and holds the plow-frame to axle A. There are three plates attached to F, which form a hinge for double or single plows.

The plow-frame E is attached by a bolt going through the plates, attached to groove F and the ends of frame E.

The plows are attached to frame E at Figures 1 and 2. The frame is held together by bolts.

The plow-frame is attached to lever B by a bolt with a joint in it, and nut on each end. One end of lever B rests on a friction-roller in post G; the other end rests on the back end of the plow-frame. The bolt passing through lever B to the frame, allows the plows to run a certain depth. Moving the nut on upper end of the bolt regulates the depth of the plows.

Lever C is attached to lever B by a hinge, and is attached to fulcrum D by a bolt.

Fulcrum D is attached to the hound N by a bolt, and is supported by a bolt going through it and post G, and it is attached to lever C with a bolt.

Post I is attached to the hound by a bolt, and catches the end of lever C when it is pressed down. When lever C is pressed down to the notches in post I, it will raise the fore end of the plow-frame first, and then it will raise the back end to a corresponding height.

What I claim as my invention, and desire to secure by Letters Patent, is—

The construction, combination, and arrangement of the axle A, hounds N, post G, with friction-roller, sliding groove F, plow-frame E, lever B, joint-bolt K, lever C, post I, and fulcrum D, as shown and described.

SAMUEL WELCH.
